(57) **CLAIM**

The ornamental design for an adhesive knee brace, as shown and described.

DESCRIPTION

FIG. 1 is a front view of the adhesive knee brace showing our new design.

FIG. 2 is a right side view thereof, in condition of use.

FIG. 3 is a front view thereof, in condition of use; and,

FIG. 4 is a left side view thereof, in condition of use.

The broken lines illustrate environmental structure and form no part of the claimed design.
